DEVICE FOR LUBRICATING ROTATING CUTTER BLADES

Charles H. Coolidge, Worcester, Mass., assignor to Curtis & Marble Machine Company, Worcester, Mass., a corporation of Massachusetts

Application March 2, 1939, Serial No. 259,374

4 Claims. (Cl. 184—64)

This invention relates to a device for lubricating the edges of cutter blades which are rotated at high speed, such as the blades of the revolving cutters of cotton or woolen shears.

5 In such machines, it is necessary that the edges of the blades be slightly but constantly lubricated, and it is also of very great importance that no substantial amount of oil be allowed to accumulate on the lubricating device or on the 10 blades, either when the machine is in operation or while it is at rest. Otherwise spots or stains may be caused which will seriously damage the goods being sheared.

It is the general object of my invention to 15 provide an improved construction of lubricating device for such purposes, which may be economically manufactured and conveniently applied to either old or new machines.

A further object is to provide a lubricating 20 device which is reliable in operation and which requires no attention by the operator to prevent continued delivery of oil by the lubricating device when the machine is stopped.

My invention further relates to arrangements 25 and combinations of parts which will be hereinafter described and more particularly pointed out in the appended claims.

A preferred form of the invention is shown in the drawing, in which:

30 Fig. 1 is a sectional side elevation of certain parts of a cloth shear, with my invention applied thereto;

Fig. 2 is a sectional plan view, taken along the line 2—2 in Fig. 1; and

35 Fig. 3 is a combined sectional and perspective view of the lubricating device.

Referring particularly to Fig. 1, I have shown portions of a cloth shear including a revolving cutter 10 having a plurality of helical blades

11, a fixed blade 12, a cloth rest 14 over which 40 the cloth C is drawn closely adjacent the fixed blade 12 and revolving cutter 10, a fixed support 15 for the blade 12, and an exhaust hood 16 by which lint and waste are removed from the shearing point. The parts thus far described 45 are of a usual construction in cloth shears.

My improved lubricating device extends the full length of the revolving cutter 10 and preferably comprises a sheet metal trough 20 having an upright rear flange 21 and a forwardly and horizontally extending front flange 22, the outer end of which is doubled and bent downward, as indicated at 23.

A cover 30 is provided for the trough 20, and 50 the rear portion 31 of the cover is offset up-

wardly and then bent downwardly, providing a U-shaped section to embrace and form a close joint with the upstanding rear flange 21 of the trough 20.

The front portion of the cover 30 is bent upwardly as indicated at 33, and is provided with a doubled inclined portion 34 forming a shield for the rapidly revolving cutter. An elongated strip of leather L is clamped between the cover 30 and the horizontal flange 22 of the trough 10 20 by a series of clamping screws 40, provided in spaced relation the full length of the oiling device.

The inner end of the leather strip L extends downward to the bottom of the trough 20, as 15 clearly shown in Fig. 3, and substantially below the level of the oil supply maintained therein. A movable oil cap 42 covers an opening in the top 30 through which the oil supply may be replenished.

The lubricating device is preferably mounted on curved arms 50 having slots 51 to receive clamping screws 52 on the exhaust head 16. The outer edge 60 of the leather strip L is to be carefully trimmed to present a straight surface, and 25 the lubricating device is to be adjusted toward the revolving cutter blades until it is just possible to see light between the edge of the leather and the edges of the blades.

With the parts thus constructed and adjusted, 30 it is found that a sufficient supply of oil will be drawn upward through the leather L by capillary attraction or wick-like action, so that the edge 60 will have an extremely thin film of oil thereon which is continuously transferred to the rapidly revolving cutter blades as they pass 35 closely adjacent thereto with a wiping effect but preferably with no actual contact between the blades and the leather strip.

Consequently, no substantial wear of the edge 40 60 of the leather strip occurs, and furthermore, the edge is not hardened by repeated blows of the blades thereon.

It will be noted that the edge of the leather strip L is substantially above the level of the oil 45 in the trough 20, so that even when the machine is at rest there is no tendency of the leather to syphon out excess oil nor to empty the trough, as is the case in any such device where the delivery point is below the oil level. Consequently, 50 the operator need give no attention to the oiling device when shutting down the machine nor when again placing the machine in operation.

My lubricating device has the very great advantage that it operates equally well and without 55

adjustment when the direction of rotation of the revolving cutter is reversed. This is very important in certain types of machines in which the cutters are repeatedly reversed during the operation of the machine.

This lubricating device has been found much more satisfactory than leather flaps resting on the revolving blades, which have been heretofore commonly used and which required frequent removal and more or less prolonged soaking in oil when the oil therein was exhausted.

It thus appears that my improved lubricating device solves a somewhat troublesome problem of long standing which presented difficulties not heretofore satisfactorily overcome.

Having thus described my invention and the advantages thereof, I do not wish to be limited to the details herein disclosed, otherwise than as set forth in the claims, but what I claim is:

- 20 1. A device for lubricating rotating cutter blades which comprises an elongated oil-holding trough, an elongated oil-absorbent strip, and means to clamp said strip in fixed relation to said trough, with its inner edge immersed in oil in said trough and with its outer edge projecting beyond said trough and substantially above the normal oil level in said trough, and firmly supported in close proximity to the locus of movement of the edges of said rotating cutter blades but out of 25 actual contact with said blades.
- 25 2. A device for lubricating rotating cutter blades which comprises an elongated oil-holding trough having a horizontally extended top flange, a cover for said trough, an elongated leather strip 30 which delivers oil directly to said revolving blades,

means to clamp said strip between said flange and said cover with its inner edge immersed in oil in said trough and with its outer edge projecting beyond said flange and cover, and means to firmly support said device in fixed position 5 with the projecting outer edge of said leather strip closely adjacent the edges of the revolving cutter blades but out of actual contact therewith and substantially radial to the locus of movement of said blades.

3. A device for lubricating rotating cutter blades which comprises an elongated oil reservoir, and an elongated strip of material having capillary qualifications, one edge of said strip being immersed in oil in said reservoir, and the other 10 edge being presented at a higher level close to said rotating cutter blades but out of actual contact therewith, and said latter edge being supplied by capillary action with a thin film of oil which is removed by said rotating blades and which is 15 replenished as fast as it is removed.

4. A device for lubricating rotating cutter blades which comprises an elongated oil reservoir, an elongated strip of material having capillary qualifications, one edge of said strip being immersed in oil in said reservoir, and the other edge being presented at a higher level close to said rotating cutter blades but out of actual contact therewith, and a cover plate secured to said reservoir and clamping said strip in position, said 25 cover plate having an inclined portion projecting upwardly from said reservoir and forming a 30 guard for the revolving cutter blades.

CHARLES H. COOLIDGE. 35
